UNITED STATES PATENT OFFICE.

LOUIS P. KLEIDERER, OF HENDERSON, KENTUCKY.

DESIGN FOR A CUFF-HOLDER.

SPECIFICATION forming part of Design No. 25,172, dated February 18, 1896.

Application filed January 16, 1896. Serial No. 575,782. Term of patent 7 years.

To all whom it may concern:

Be it known that I, LOUIS P. KLEIDERER, of Henderson, in the county of Henderson and State of Kentucky, have invented and produced a new and original Design for a Cuff-Holder, of which the following is a full, clear, and exact description.

Reference is to be had to the accompanying drawing, forming a part of this specification, which represents a plan view of a cuff-holder embodying my new design.

The leading feature of my design consists in the cuff-holder having wavy lines for the major portion of its length, one end having a plurality of loops presenting a leaf-like figure and the opposite end having a large central loop with eyes at the sides. 15

I claim—

The design for a cuff-holder herein shown and described.

LOUIS P. KLEIDERER.
